A. J. CUMMING.
CARBURETER.
APPLICATION FILED OCT. 18, 1915.

1,213,462.

Patented Jan. 23, 1917.

UNITED STATES PATENT OFFICE.

ALBERT J. CUMMING, OF MINNEAPOLIS, MINNESOTA, ASSIGNOR OF FIFTY-ONE ONE-HUNDREDTHS TO WILLIAM G. JORDAN, OF MINNEAPOLIS, MINNESOTA.

CARBURETER.

1,213,462.

Specification of Letters Patent. Patented Jan. 23, 1917.

Application filed October 18, 1915. Serial No. 56,443.

To all whom it may concern:

Be it known that I, ALBERT J. CUMMING, a subject of the King of Great Britain, residing at Minneapolis, in the county of Hennepin and State of Minnesota, have invented certain new and useful Improvements in Carbureters; and I do hereby declare the following to be a full, clear, and exact description of the invention, such as will enable others skilled in the art to which it appertains to make and use the same.

My invention has for its object to provide an extremely simple and highly efficient carbureter primarily for internal combustion engines; and to such ends, generally stated, the invention consists of the novel devices and combinations of devices hereinafter described and defined in the claims.

A Venturi tube, as is well known, is one which has a contraction at some point so that the air or other fluid passes at relatively high velocity at the contracted portion, and such tubes are extensively used in carbureters, but it is customary to provide in the same, yieldingly seated valves which open variably under varying suction, and hence, vary the conducting capacity of the tube substantially proportionate to the force of the suction or partial vacuum created in the tube.

My invention involves a radical departure from the above just noted customary arrangement and consists in providing in the Venturi tube of the carbureter fixed baffles or obstructions located between the air intake end of the tube and the point where the volatile hydrocarbon or fluid fuel is drawn into the said tube.

This improved carbureter is not only well adapted for use in carbureting air with highly volatile fluids, such as gasoline and alcohol, but is capable of use for vaporizing a heavier volatile liquid, such as kerosene, for example.

In the accompanying drawings which illustrate the invention, like characters indicate like parts throughout the several views.

Referring to the drawings: Figure 1 is a vertical section taken centrally through the improved carbureter, some parts being shown in full; Fig. 2 is a transverse section taken on the line $x^2 x^2$ of Fig. 1; some parts being shown in full; and Fig. 3 is a detail in section on the line $x^3 x^3$ of Fig. 2.

The tortuous air intake conduit 1 of the

carbureter constitutes a Venturi tube and is formed in a casing 2 that preferably is provided at its central portion with a depending tubular stem 3. In the intake end of the conduit 1, is a choke valve 4 shown as of the "butterfly" type. This choke valve is of the customary construction and may be operated in the usual or any suitable way, but normally, would be held open by a spring, or otherwise, and would have a suitable connection extending to within reach of the operator, such being the customary construction. In the delivery end of the conduit 2, to-wit, in the end which is connected to the explosion chamber, through an intake manifold, or otherwise, is a throttle valve 5, preferably also of the "butterfly" type. This throttle valve is also preferably of well known construction and would be operated in the usual, or any suitable way, being, as shown, provided with a diametrically extended vertical shaft 6 journaled in the casing 2 and provided at its upper end with an arm 7, which latter would have a suitable operating connection extending to within an easy reach of the operator.

The intermediate portion of the top of the casing 2 is provided with a threaded seat and, as shown, also a threaded bushing 8, both axially aligned with the passage in the tubular stem 3. A needle valve 9 is adapted to open and close the upper extremity of the passage through the tubular stem 3, and this needle valve has a threaded portion 10 that engages the threaded seat in the top of the casing 2 and has a smooth portion that works with close engagement through the bushing 8. At its extreme upper end, the needle valve 9 is provided with a suitable hand piece in the form of a knurled head 11. Here it should be noted that the bottom of the casing 2 and the lower intermediate portion of the conduit 1, immediately surrounding the axial passage of the tubular stem 3, are depressed to form a small bowl-like cavity 12. Just inward of the choke valve 4, the casing 2 is provided with a raised baffle flange 13, and farther inward, the top of the said casing 2 is provided with a depending baffle flange 14. These baffle flanges 13 and 14 cause the air drawn in through the receiving end of the conduit 1, to take a tortuous downward and then upward course, so that the air drawn in sinks rapidly

through, or over the bowl 12, and produces a suction which serves to draw the fluid fuel through the tubular stem 3, as will herein-after more fully appear.

The numeral 15 indicates a cup for holding the fluid fuel. This cup is preferably of spun or pressed metal, which surrounds the stem 3, and is tightly seated against the lower end thereof, with its upper edge tightly seated against an annular jointed surface 16 formed on a horizontally extended flange 17 of the casting 2. Preferably, the cup 15 is thus secured to the stem 3 by the casing of a drain cock 18 which has a reduced threaded portion that is screwed into internally threaded seat of the said stem 3 in such manner that it forms a continuation of the conduit through the said stem 3. A shouldered portion of the casing 18 tightly clamps the bottom of the cup 15 against the lower end of the stem 3, thereby forming a liquid-tight joint therewith. The passage in the drain tube 18 is normally closed by a valve 19. At points just above the threaded upper end of the tube 18, the tubular stem 3 is provided with intake ports 20 which are always below the level of the fluid fuel y that is contained within the cup 15.

Within the cup 15 and loosely surrounding the stem 3 is an annular float 22 preferably of cork coated with shellac. This float 22, at one side, is hinged at 23 to the flange 17 of the casing 2.

The fluid fuel is supplied to the carbureter from a suitable source, through a pipe 24, as shown, which is screwed into a sleeve-like projection 25 of the casing 2. The cavity in this projection 25 is connected to the fuel cup, through a port 26 and a depending valve seat 27 formed in said casing. In the said valve seat 27 is a gravity retracted fuel supply valve 28, the upper end of which is conical and is adapted to close the port 26 when forced upward. As shown, the body of this valve 28 is rectangular, so that clearance is afforded between the same and the seat 27 for the passage of the fluid fuel. The reduced lower end of said valve 28 rests upon the float 22. When the fluid fuel reaches a certain altitude, the float 22 will cause the valve 28 to close the intake port 26 and cut off further supply of the fuel to the cup 15; and when the altitude of the fluid fuel has been reduced slightly, the float 55 drops and causes the valve to open the said port 26 and permit a further supply of the fuel to the said cup. In this way, the altitude of the fluid fuel in the cup 25 is automatically maintained.

When the engine is in operation, the air drawn through the conduit 1 will draw up the volatile fluid fuel through the tubular stem 3 and thereby carburet the air. The richness of the mixture may be varied by 65 adjustments of the needle valve 9 and the

amount of the explosive mixture drawn into the engine may be regulated in the customary way, by adjustments of the throttle valve 5. To insure the desired initial supply of fluid fuel to start the engine, it is often 70 desirable to temporarily close the choke valve 4 so that greater drawing or suction action will be produced in the tubular stem 3.

From a broad point of view, the so-called 75 "baffle flanges" 13 and 14 afford immovable obstructions which offer a constant resistance to the passage of air through the air intake conduit, in contradistinction to carbureters having spring pressed valves which 80 move, and hence, vary the air conducting capacity with each impulse. In practice, I have found that highly improved results can be obtained by arranging permanent or immovable air obstructing flanges or baffles in 85 the air intake conduit, as above described, and relying entirely on the throttle valve at the delivery end of the tube to vary the delivery capacity of the carbureted air, except in starting, when the choke valve is sometimes used.

When the carbureter is in normal action, the so-called choke valve performs no function whatever. To obtain the best results, the so-called baffles should be arranged to 95 cause the air to take a zig-zag course through the tube and to make a downward sweep immediately over the fluid fuel intake port. As these baffles afford a contraction in the tube close to the fluid fuel intake port, 100 but on the air receiving side thereof, the in-drawn air is caused to pass with high velocity at a point close to the fuel intake port and then is permitted to expand in the chamber which immediately overlies the said 105 fuel intake port. In this way, the suction required to pick up the fluid fuel is afforded and the air is caused to thoroughly commingle with the fuel or hydrocarbon vapor. The above statements are based on actual 110 use of the above described carbureter.

The carbureter described, as is obvious, is of very simple construction, may be made at small cost, has no parts that are likely to get out of order. Furthermore, it does not 115 require fine adjustment of tuning up, as do carbureters having spring-pressed valves arranged to be opened and closed under varying impulses.

What I claim is:

1. In a carbureter, a casing having an air passage in the form of a Venturi tube with a depressed bowl and fuel intake port opening into said bowl, said tube having its greatest contraction at one side of said bowl, 125 and at a point between said fuel intake port and the air intake end of said tube, and the said tube at a point between said air intake and its point of greatest contraction, also having a permanently fixed baffle flange. 130

2. In a carbureter, a casing having an air passage in the form of a Venturi tube with a depressed bowl and a fuel intake port opening into said bowl, said tube having its greatest contraction at one side of said bowl and at a point between said fuel intake port and the air intake end of said tube, and the said tube, at a point between its air intake end and its point of greatest contraction having a permanently fixed baffle flange that rises above said bowl.
3. In a carbureter, a casing having a tube for the intake of air, a fluid fuel intake port opening into the bottom of the intermediate portion of said tube, fixed baffle flanges in said tube between the intake end thereof and the said fuel port, the said baffle flanges being arranged to afford a contraction in the said tube and to cause the air to take a zig-zag downward course on its way past the said fuel port, a throttle valve in the delivery end of said tube, and a choke valve in the receiving end of said tube adapted to be set in a position at one side of the passage through said tube, the said baffles projecting, one upward and one downward, and arranged to afford a contraction of the said tube and to cause the air to take a zigzag

downward course on its way past said fuel intake port.

4. In a carbureter, the combination with a casing having an air intake conduit and a depending tubular stem communicating with the intermediate portion of said air intake conduit, a needle valve working through the top of said casing and serving to open and close said tubular stem, said intake conduit having, on the receiving side of said needle valve, upwardly and downwardly extended baffle flanges, a choke valve in the receiving end of said air intake conduit working adjacent to the upwardly extended baffle flange, a throttle valve in the delivery end of said air conduit, and a cup having communication with the said tubular stem for the supply of the fluid fuel thereto, and means for automatically maintaining an approximately constant level of fluid fuel in said cup.

In testimony whereof I affix my signature in presence of two witnesses.

ALBERT J. CUMMING.
